SIGN

Filed Dec. 12, 1931

UNITED STATES PATENT OFFICE

AUSTIN A. WOOD AND EDWARD BOSS, OF COLUMBUS, OHIO

SIGN

Application filed December 12, 1931. Serial No. 580,585.

This invention relates to metallic sign structures and has for its primary object the provision of a durable and economically constructed sign adapted for use in outdoor locations, as, for example, along highways or thoroughfares, for the purpose of attractively displaying advertising and other publicity matter.

It is another object of the invention to provide a metallic sign structure which will require but a minimum of space in effecting its erection and use and yet one which will possess a greater degree of mechanical strength than the usual form of signs of comparable nature.

A further object of the invention rests in the provision of means by which the advertising or display panels may be removably mounted in connection with a supporting standard or post for the sign permitting the panels with any copies of advertising matter thereon to be readily changed without loss of time to the advertiser.

With these and other objects in view, which will appear as the description proceeds, the invention consists in the novel features of construction, combinations of elements and arrangements of parts hereinafter to be more fully described and pointed out in the appended claim.

In the accompanying drawing:

Figure 1 is a perspective view of the improved sign structure comprising the present invention,

Figure 2 is a side elevation thereof on an enlarged scale having portions of the structure broken away to show underlying structure,

Figure 3 is a horizontal sectional view taken on the line indicated by the numerals 3-3 of Figure 1, and

Figure 4 is a detail vertical sectional view on the line 4-4 of Figure 2.

Referring more particularly to the drawing, the numeral 1 designates our improved sign structure in its entirety, which in this form has been shown as having the shape of a banner to give the sign an outstanding and pleasing appearance. The said structure in this instance is formed to comprise a sup-

porting standard or post 2 preferably formed of metallic tubing and having a suitable height and cross-sectional area to support the sign structure in an efficient manner. The lower end of the standard or post 2 is preferably embedded or set in the ground with sufficient concrete or other cementitious material 3 to insure a straight and rigid connection for the standard.

The post 2, which is of such height that the sign is clearly visible from a considerable distance carries at its upper portion a pair of metallic plates or panels 4 on the outer surfaces of which advertising material may be carried and applied in any well known manner. The plates 4 have their lower edges bevelled as at 5 and are of such width as to simulate a banner and the lower edges may be further ornamented as at 6 to give this appearance. These panels, which are arranged one on each side of the post 2, are connected centrally thereof to said post by means of studs or other fastening elements 7 which extend through aligned openings 8 formed in the post 2 and have their outer ends equipped with clamping nuts 9 to hold the studs in rigid connection with the supporting post or standard 2. The outer threaded ends of the fastening members 7 are of sufficient length to protrude through openings formed in the panel members and which are held in place thereon by a second set of clamping nuts 10 for drawing the plates into firm supporting engagement with the sides of the supporting standard. By means of this connection it will be readily seen that either of the plates 4 may be disconnected from engagement with the supporting post member 2 without materially interfering with the other of the panels and will permit of the erection of each plate separately as the same are of considerable size and weight when used for highway advertisements. This is of particular importance in that the panels may thus be readily changed enabling old plates to be removed and new ones erected with new advertising matter thereon.

To provide for more rigidity of the sign, the outer side edges of the plates 4 may be

fastened together by bolts 11 so as to close the side edges between the respective panels and to give the sign a substantially oblong transverse cross-section. Due to the drawing of the plates 4 together in this manner at the edges, not only is more rigidity provided but, due to the slight curvature of the outer surface thereof, better visibility of the advertising matter is afforded in that it tends to eliminate glare and break up light rays reflected from the sun. The sign, which represents a banner, is provided with a pair of ornamental rods 12 formed of tubing and are flat at their outer ends as at 13 for their attachment between the edges of the plates 4 into the upper of the fastening elements 11. The other or upper ends of the rods 12 are bent slightly inwardly towards one another and extend into an opening formed in an ornamental top piece 14 which is shaped to represent a ball or sphere and has a depending portion 15 extending into the upper end of the standard or post 2. The top piece 14 may be held in place at the upper end of the post by the connections with the rod 12 or anchored in any suitable manner well known in the art. The rods 12, which may serve to stabilize the upper or outer ends of the panel members or plate 4, are primarily employed to represent the attaching cords which are commonly found in banner constructions and may be ornamented to represent such cords if desired.

In view of the foregoing it will be seen that the present invention provides a simple, positive and effective sign structure particularly adapted for the display of outdoor advertising matter such as roadsigns and the like. One of the features of the invention resides in the ease with which the advertising matter may be changed. The panels are preferably made at a suitable factory with the advertising matter thereon. The replacement of panels may be readily accomplished by the removal of the clamping nuts 10 and the bolts 11 enabling either or both of the panels to be withdrawn and the entire substitution effected in the space of but a few minutes. This is in contrast to many forms of signs which usually require repainting at the place of erection or the tacking or pasting of posters on the display surfaces. The sign structure possesses a very considerable degree of strength and when erected requires but a minimum of ground space, the same being devoid of laterally and angularly extending props or braces which are objectionable in many places and which interfere with the use of the soil between or around the braces. This is one of the reasons, among others, why the present sign is more economical to erect and maintain than those of comparable nature since the leasing rentals are considerably lower due to the minimum space occupied. Due to the double panels used the

sign performs double duty in that they show equally well in both directions without the supporting standard or post interfering with the advertising material thereon.

It will be appreciated that the sign may be made in any desired size without departing from the spirit of the invention. Slight changes may, of course, be made by those skilled in the art such as the mode of fastening the panels in place and other various details, and we therefore intend to cover as our invention all such structural variations as may be said to fall fairly within the spirit and scope of the subjoined claim.

What is claimed is:

A metallic sign structure having the general outline of a banner comprising a single supporting standard formed of suitable length and cross sectional formation having its lower end anchored in connection with a supporting surface, a pair of opposed advertising panels carried by the upper portion of said standard and arranged one on each side thereof, fastening elements having threaded extremities projecting from said standard for detachable connection with said panel, said fastening elements permitting the removal of one of the panels without disturbing the connection for the other, additional fastening elements uniting the outer side edges of the panels for drawing the panels into a slightly oblong formation when viewed in plan, the upper end of said standard extending a distance above said panels and provided with an ornamental top piece, and angularly arranged rods extending from the upper corner edges of the panels and having a connection with said top piece, said rods serving to unite said top piece with the upper end of said standard.

In testimony whereof we affix our signatures.

AUSTIN A. WOOD.
EDWARD BOSS.
